UNITED STATES PATENT OFFICE.

GEORGE H. FRITZSCHE, OF BROOKLYN, NEW YORK.

DESIGN FOR A DISPLAY TOY.

Application filed July 11, 1923. Serial No. 6,752. Term of patent 3½ years.

To all whom it may concern:

Be it known that I, GEORGE H. FRITZSCHE, a citizen of the United States, and resident of the borough of Brooklyn, in the city and State of New York, have invented a new, original, and ornamental Design for a Display Toy, of which the following is a specification, reference being had to the accompanying drawing, forming part thereof.

The drawing represents a perspective view of my new design for a display toy.

The design consists generally, of a front or facade of open formation, a rear wall, side walls flaring forwardly from the rear wall to the front, and counters disposed adjacent the walls.

I claim:

The ornamental design for a display toy substantially as shown and described.

GEORGE H. FRITZSCHE.
